AIR POWERED HAIR CLIPPER

Henry Dreyfuss, South Pasadena, Calif., assignor to Preco Incorporated, Los Angeles, Calif., a corporation of California

Filed May 14, 1964, Ser. No. 79,981

Term of patent 14 years

(Cl. D22—3)

FIG. 1 is a perspective view of an air powered hair clipper showing the top, the front end and one side of my new design;

FIG. 2 is side elevation;

FIG. 3 is a front end elevation;

FIG. 4 is a rear end elevation; and

FIG. 5 is a bottom view.

I claim:

The ornamental design for an air powered hair clipper, substantially as shown.
